(57) **CLAIM**

The ornamental design for an “adjustable frame for displaying multiple photographs”, as shown and described.

DESCRIPTION

FIG. 1 is a front perspective view of an “adjustable frame for displaying multiple photographs” showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a perspective view showing the manner in which the invention may be used.
